his attorney.

UNITED STATES PATENT OFFICE.

WILBERT G. WISE, OF AKRON, OHIO, ASSIGNOR TO THE WISE FURNACE CO., OF AKRON, OHIO, A CORPORATION OF OHIO.

WATER-HEATER.

1,013,094.

Specification of Letters Patent.

Patented Dec. 26, 1911.

Application filed June 8, 1910. Serial No. 565,800.

To all whom it may concern:

Be it known that I, WILBERT G. WISE, a citizen of the United States, residing at Akron, in the county of Summit and State 5 of Ohio, have invented certain new and useful Improvements in Water-Heaters, of which the following is a specification, reference being had to the accompanying drawings, forming a part thereof.

10 My invention relates more particularly to a water-heater designed for heating buildings; the requirements being the maintenance of a maximum circulation of water at the desired heating temperature, for the 15 amount of fuel consumed.

This invention, as herein embodied and set forth, comprises a sectional water-heater, wherein the circulation is effected largely by the inclined and staggered transverse 20 water-tubes, which are given such inclination as to cause the water to flow within the heater transversely and circumferentially. Moreover, the adjacent sections of said 25 heater are so constructed as to assist in bringing the water to the desired temperature and directing the products of combustion about the heater-section most effectually.

The details of my invention will be very 30 readily understood upon making reference to the accompanying drawings, wherein:—

Figure I is a vertical section through a water heater embodying my improvements; the same being mounted upon a base of suitable 35 form, and somewhat diagrammatically indicated in said drawings. Fig. II is a perspective view of the heater-section containing the transverse water-tubes; and Fig. III is a detail showing two of the outer 40 transverse tubes and a slightly modified construction.

Throughout the several figures of the drawings, I have employed the same character of reference to indicate similar parts.

45 It should be understood that the base B, the fire-box and the accompanying heater-sections may be of the desired type, since the principal features of my invention are present in the intermediate heater-section shown in Fig. II. I preferably associate therewith the fire-box α , which has hollow walls and is surrounded by a body of water. Immediately above the fire-box and connecting therewith is the hollow crown b , having circumferential apertures b' permit-

ting the passage of the products of combustion. Superposed upon the fire-box section is the improved heater-section c , having alternately inclined central water-tubes c' , the end tubes of greater inclination c^2 c^3 , 60 and the connecting circumferential openings c^4 for said section. These members preferably are integrally cast, and serve materially to augment the heating effect and circulation of the water. The top section d 65 also is hollow and is provided with a central opening d' through which the products of combustion are directed beneath the dome e to the outlet or flue f , connecting with the chimney stack.

70 Referring to Fig. II, I have indicated by means of darts, the direction of the flow of water in the heater-section c , and the circulation of the products of combustion from the fire-box and about the tubes within the 75 heater-section will be apparent by referring to Fig. I. From this showing, it will be readily understood that the inclined pipes are subjected to the heated gases and products of combustion, first directed circumferentially against the side inner walls of the heater-section c , and then drawn toward the center through the opening d' in the superposed section d . As a result thereof the water in heater-section c is equalized in 80 its circulation, and is directed circumferentially at either side through the inclined pipes c' . The end pipes c^2 , which are farthest from the vertical connecting outlets, are given greater inclination; rising from 85 the common central inlet c^5 . In Fig. III, a second set of pipes c^2 is likewise shown connected with said inlet c^5 , and a plurality of such pipes may be employed as desired where the height of the heater-section is not 90 sufficient to give the desired inclination, or a greater circulatory effect is required. At the opposite side of heater-section c , the pipes c^3 rise from the terminals of a chord, to the common exit c^6 ; the inclination of 95 said pipes being greater than the central transverse pipes c' and substantially that of the pipes c^2 . Since the pipes c^2 and c^3 are sharply divergent from or to a common inlet across a short chord of the heater section, at the front and back thereof, it is apparent that their inclination and circulatory 100 effect is greater than that of the intermediate and longer pipes c' . This will be immediately noted upon viewing the upper 105 110

portion of the central vertical section, Fig. I, which indicates that the pipes c^2 and c^3 have their total inclination from top to bottom of the heater section, at either side of a 5 bisecting vertical plane. The common inlet c^5 , and the outlet c^6 , accordingly contribute to the maximum circulation obtainable within restricted spaces; the one supplying water to the inclined pipes c^2 , and the other serving 10 as a common exit for the water from the pipes c^3 , when the water heater is in operation. As best shown in Fig. II, the pipes and the connecting annular water-chamber are integrally cast, to avoid any chance of 15 leakage. Thus, all of the available heating space within the heater-section c is effectively utilized, and the pipes are so arranged and given such inclination as to insure the maximum heating effect and equalized circulation 20 of the contained water. Adjacent heater-sections contribute to this; the crown b with its depending center b'' assisting to secure the circumferential flow of the water, while the openings b' direct the heat 25 most effectually within the heater-section c .

Having now explained the structural features and general operation of the water-heater embodying my invention, I claim as new, and desire to secure by these Letters 30 Patent, the following:—

1. A water-heater section comprising a horizontal chambered or hollow annular member, and a plurality of connecting transverse tubes interiorly thereof, which are 35 sharply inclined and extend between connections positioned respectively at the upper and lower levels of said member upon either side of a vertical bi-secting plane, substantially as set forth.

2. In a water-heater, the combination with 40 a fire-box, of a superposed crown having peripheral passages or flues, a horizontal water heater-section positioned above said crown and equipped with a plurality of 45 transverse inclined pipes positioned immediately above the peripheral flues, and a central dome connecting with the chimney-stack, substantially as set forth.

3. In a water-heater, the combination with 50 a fire-box, of a chambered crown having peripheral passages or flues, a superposed connecting water heater-section, comprising a chambered annular member and transverse inclined pipes within said member immediately 55 above the flues, respectively connecting

with a common opening and sharply inclined divergently to separate connections at either side of the annular member, and a central dome above said section connecting with the chimney-stack, substantially as set forth.

4. A water-heater section comprising a horizontal chambered inclosing member, and transverse inclined pipes therein extending substantially from the upper to the lower 65 levels of said section, connected with a common opening and sharply inclined divergently to separate connections at either side, substantially as set forth.

5. A water-heater section comprising a 70 chambered inclosing member, transverse inclined pipes therein connected with a common opening and sharply inclined divergently to separate connections at either side, and inclined transverse pipes positioned in 75 staggered relation within said member and extending from top to bottom and bottom to top respectively, substantially as set forth.

6. A water-heater section comprising an annular member c , divergent inclined pipes 80 c^2 c^3 respectively connecting with a common inlet and outlet at opposite sides, and intermediate inclined pipes c' in alternately staggered relation, substantially as set forth.

7. In a water-heater, the combination with 85 a fire-box, of a chambered crown provided with peripheral flues, a superposed water heater-section connecting therewith equipped with transverse inclined pipes, and a superposed section thereon having a reduced central opening for the passage of the products of combustion, substantially as set forth.

8. In a water-heater, the combination with 90 a suitable fire-box, of a chambered crown having peripheral passages or flues, a superposed heater-section comprising an annular member having water heating pipes transversely inclined interiorly thereof in alternate relation, and a superposed member provided with a reduced central opening for 95 withdrawing the products of combustion interiorly of the heater-section, substantially as set forth.

In testimony whereof I affix my signature in presence of two witnesses.

WILBERT G. WISE.
